UNITED STATES PATENT OFFICE.

HERMAN L. STRONGSON, OF BROOKLYN, NEW YORK, ASSIGNOR TO LOEB-STRONGSON CORPORATION, OF NEW YORK, N. Y., A CORPORATION OF NEW YORK.

POURING SPOUT.

1,405,638.

Specification of Letters Patent. Patented Feb. 7, 1922.

Application filed July 26, 1920. Serial No. 399,213.

To all whom it may concern:

Be it known that I, HERMAN L. STRONGSON, a citizen of the United States, residing at Brooklyn, in the county of Kings and 5 State of New York, have invented certain new and useful Improvements in Pouring Spouts, of which the following is a specification.

This invention relates to pouring spouts 10 for decanting liquids from cans, and more particularly to improvements in pouring spouts.

An object of the invention is to produce an improved type of pouring and decanting 15 device which is easily cleaned, is sanitary, and furthermore which is simple and inexpensive to manufacture; and one which also serves the purpose of a can opener to cut a large opening in a can.

20 One practical example of a pouring spout, representing my invention, is illustrated in the attached drawings, wherein:

Figure 1 shows a longitudinal section of the device; and Figure 2 shows it in elevation anchored to a can, the can being in 25 section to disclose the way in which the spout so effectively clamps itself on the can, to form a liquid proof joint.

Figure 3 shows a bottom view of Figure 30 2; and Figure 4 shows a bottom view of a can which has been punctured or cut open by the cutting blade of the spout with said spout removed.

Figure 5 shows a modified one piece construction, preferably used in the manufacture of pouring spouts.

With further reference to the drawings, there is shown a tubular body 6 open at each end, and provided with a hinged cover 7 40 which conveniently opens and closes to expedite the use of the pouring spout. It is practical to make the upper end of the tubular body rectangular and also form it smaller than the central body portion so as 45 to produce a shapely and neat appearing household utility. This construction simplifies the fitting on of cover 7, and likewise provides flat surface which permits the user's hand to gain a firm grip on the device so 50 as to push it into a can top. The lower end of the tubular body is preferably shaped in the form of a cylinder, and a flange 8 is formed on the shoulder to provide a recess which receives a similarly shaped blade and 55 gasket.

A blade 10 is made cylindrical in form with a flange 9 turned outwardly on the upper edge. This flange is firmly seated within the flange 8 of the tubular part 6, and by a spinning or swedging process during 60 the course of manufacture, the outer part 8 is firmly set up against the inner part 9. In this way the two main members 6 and 10 are joined together to constitute the pouring spout. A gasket 11 is pressed into the 65 space formed by the flange 8, and makes the spout fit onto a can with a liquid proof connection.

The tubular blade has oppositely disposed puncturing points 12. Cutting edges 13 extend upwardly from the points on one side of the cylindrical blade to form a flat non-cutting edge or surface 14, while on the other side of the tubular body the edges 13 recede from the points 12 and intersect to 70 make a cut-out point 15. The cut-out corner 15 and non-cutting edge 14 are about oppositely disposed; and it is noted that the edge 14, since it is designed to not cut through the can top, is located above the 75 cut-out point 15 and just below the exposed surface of the gasket so that it will bend and force downwardly the tin section which the cutter blade severs from the can top.

Struck-out points or barbs 17 are formed 80 in the tubular blade 10 and made opposite one the other, and being disposed relatively close to the gasket. The barbs or points have gradually inclined edges which allow 85 them to slip over the edges of the cut tin top as later explained. It is the preferred practice to make two barbs on the round blade member, but more may be used if necessary. The points of the barbs 17 lay 90 back one from the other to permit the device to be rotated without the barbs hanging or cutting into the cut tin edge.

To insert the pouring spout in a can, one 95 firmly grips the body 6 in his hand and thrusts the points 12 into a can to start the blade 10 on its cutting operation. Continued pressure pushes the blade edges 13 through the can until the cut-out point 15 passes clear through the metal can top. The non-cutting edge does not cut through the metal 105 and hence leaves a small uncut neck B to hold the cut top C intact with the can top D.

The pouring spout is now given a slight 110 turn which causes the barbs 17 to tightly

climb or bear against the cut tin edge of the can, and this action of the barbs causes the spout to firmly anchor itself on the can. The device is usually given about one-quarter

5 turn which causes the cut tin center C to be bent over to one side away from the opening made in the can, thus leaving a large unobstructed hole cut through which the contents of a can may pour.

10 The heaviest liquids find ready egress through the large opening made in the can and through the large unobstructed opening through the pouring spout.

This type of pouring spout has the advantage 15 of the large passageway through the blade and tube, and there is no cutting blade or bar disposed in the path of liquid flow such as hinders other less improved spouts. This design of pouring spout is

20 easier to wash and clean than others and fills a household utility need where canned foods and substances of all kinds are used. It likewise may be used for cutting round holes in cans or other objects as explained

25 and shown in the drawings.

The pouring spout shown in Figure 5 is constructed from a single tubular member 20 and has the puncturing points, and char-

acteristic features of the other type spout. Its gasket 11 is held in a suitable flanged 30 ring 21 which is pressed, soldered, or otherwise anchored on the tube 20.

Having described the invention, claims are made therefor as follows:

A pouring spout through which liquids 35 may be decanted, comprising a tubular member, a cutting blade made on the member and having edges which converge to make oppositely disposed puncturing points, the said cutting blade made with a sharp cut- 40 out corner to produce a cut in a container, the said blade having a dull non-cutting edge formed oppositely to the cut-out corner to force downwardly the cut part of the container in such a manner that the said 45 cut part is forced out of the pouring spout, a gasket to make a sealed joint between the pouring spout and container, and lugs to engage the edges of the container to hold the gasket and pouring spout in position after 50 the cut part is forced out of the pouring spout.

In witness whereof I hereunto affix my name this 23rd day of July, 1920, in the city of New York.

HERMAN L. STRONGSON.
